UNITED STATES PATENT OFFICE.

GEORGE W. BANISTER, OF FOREST HILLS, MASSACHUSETTS.

BAG-SUPPORT.

1,294,753.

Specification of Letters Patent.

Patented Feb. 18, 1919.

Application filed June 5, 1918.

Serial No. 238,248.

To all whom it may concern:

Be it known that I, **GEORGE W. BANISTER**, a citizen of the United States, and resident of Forest Hills, county of Suffolk, State of Massachusetts, have invented an Improvement in Bag-Supports, of which the following description, in connection with the accompanying drawing, is a specification, like characters on the drawing representing like parts.

This invention relates to improvements in bag supports and the object thereof is to provide means for retaining the bag in extended position at all times so that it will not collapse when placed upon a floor, table or counter and opened for the purpose of introducing articles into it or removing them therefrom.

A further object of the invention is to provide a device of the character described which will properly support the bag while permitting it to be opened and closed without interfering with the hinged frame which surrounds the mouth of the bag.

Another object of the invention is to provide a bag support of the type referred to which may either be made up in the bag between the outer wall and lining thereof or which may be introduced into standard bags after they have been made up.

Other objects and features of the invention will more fully appear from the following description and the accompanying drawings and will be pointed out in the annexed claims.

The invention is illustrated herein as applied to a standard bag known commercially as the "Boston" or "student's" bag and also in a slightly different form as applied to a cloth or other bag made of flexible material throughout.

In the drawings,

Figure 1 is a vertical longitudinal sectional view through a "Boston" or "student's" bag with my invention embodied therein,

Fig. 2 is an end view of a "Boston" or "student's" bag embodying my invention showing in full lines the bag in closed position and in dotted lines in open position,

Fig. 3 is a perspective view of a preferred form of bag holder removed from the bag and

Fig. 4 is a perspective view of a bag made of flexible material throughout having a support therein embodying my invention.

The "Boston" or "student's" bag which is illustrated in Figs. 1 and 2 comprises a generally rectangular bottom 1 of rigid material having its corners rounded. The edge 2 of the body portion of the bag is secured to this rigid bottom 1 and is provided with upwardly and slightly inclined sides 3, 4 and ends 5, 6. The sides and ends of the bag are usually formed of a single piece of leather or other material of uniform height throughout and the top reinforced with a steel frame of substantially the same dimensions as the bottom and which when opened to horizontal position will present an opening substantially of the same area as the bottom of the bag.

The frame desirably is constructed of steel or other suitable material comprising two U-shaped members 7, 8 which are hinged together at their ends by pivots 9, 10 and the upper edge of the wall of the body is wrapped around the frame and secured to it in any desired manner. The bag thus constructed may or may not be provided with a lining. Suitable handles 11, 12 are secured to the central portion of said frame so that both may be grasped by the hand at the same time. A suitable strap 13 secured to one side and having a buckle 14 connected to the other side is usually provided for retaining the mouth of the bag in closed position. The bag thus described is one of standard manufacture.

A preferred form of bag support which is applicable to a bag of this character is illustrated in Fig. 3 and comprises a rectangular base 15 preferably made of a continuous piece of wire shaped to conform to and fit the bottom of the bag. Resilient supporting members are secured preferably to the ends 16, 17 of this rectangular frame. These supporting members desirably are formed of wire which is bent to present two parallel shanks 18, 19 having a loop formed of outwardly bent portions 20, 21 and a connecting portion 22, the loop forming a T-shaped support adapted to fit the end portion 23 of the bag which is bent downwardly by the frame when the bag is closed.

The lower ends of the shanks 18, 19 are wrapped about the ends 16, 17 of the frame 15 and their terminals are secured thereto by solder 24 or in any other suitable manner.

The stems 18, 19 are preferably wrapped around from the outside toward the inside so that spiral springs are formed about the

- ends 16, 17 of the frame which tend always to force the upper ends of said stems outwardly and retain the ends of the bag in extended position as illustrated in Fig. 1.
- 5 The end supporting means 18, 19 desirably are of such length that the horizontal portions 22 of the loops at their upper ends will be substantially in the horizontal plane of the pivots 9, 10 when the frame is in open position as illustrated in Fig. 2. When the end supporting means are of this height they will stretch the portions 23 of the bag taut and aid in retaining the frame in open position as they then become in effect studs 15 supporting the hinges of the frame.

By this construction the bag may be much more conveniently used, for in bags of this character the sides are usually constructed merely of leather or a flexible substitute material and as soon as the material has lost its original stiffness the bag has a tendency to collapse when set down.

While I have described the invention as particularly applicable to the "Boston" or "student's" bag it will be obvious that it may be used to support various other forms of bags and that its size, shape and form may be modified to fit the particular bag to which it is adapted. In Fig. 4 a modified form of the bag support is shown as applied to a bag which is formed of fabric throughout and which has no rigid bottom. In this construction the support comprises merely a U-shaped member made of wire or other suitable resilient material having a base portion 25 and side members 26, 27 extending substantially at right angles thereto.

The side members 26, 27 desirably are provided at their upper ends with loops 28, 29 which may be of any desired size and which will serve the double function of aiding in stretching the mouth of the bag and of preventing wear upon the material of which the bag is made.

45 The bag illustrated in Fig. 4 is provided with a puckering string 30 suitably run through a hem 31 in the bag. It will however be understood that if desired a bag support similar to that illustrated in Fig. 3 50 having a base of any desired width may be inserted in a flexible bag of the character illustrated in Fig. 4.

It will be understood that the embodi-

ments of the invention disclosed herein are illustrative merely and not restrictive and that various modifications in size, form, material, and arrangement of parts may be made within the spirit and scope of the following claims.

Having thus described my invention what I claim as new and desire to secure by Letters Patent is;

1. In combination with a bag comprising a base, a body having sides and ends extending upwardly therefrom and a hinged top frame; a bag support comprising a base conforming substantially to the base of the bag and adapted to rest upon the same and upwardly extending resilient members engaging the end portions of the bag beyond the ends of the frame and supporting the end portions of the bag and adapted to permit the hinged ends of the frame to pass between them when the bag is closed.

2. In combination with a bag comprising a base, a body having sides and ends extending upwardly therefrom and a hinged top frame, a bag support comprising a base conforming substantially to the base of the bag and adapted to rest upon the same and upwardly extending resilient members engaging the end portions of the bag beyond the ends of the frame thereby supporting the end portions of the bag but acting to permit the hinged ends of the frame to pass between them when the bag is closed and means for causing said upwardly extending supporting members normally to press the ends of the bag outwardly.

3. A bag support comprising a rectangular skeleton metallic base frame, supporting means for the ends of a bag secured thereto comprising wires bent in the middle to form parallel stems and having at the bent portions loops forming T-shaped supports to engage the ends of the bag, the free ends of said wires being coiled about the ends of the skeleton frame and secured thereto to form spiral springs adapted to force the looped portions of the supporting members outwardly to expand and to prevent the collapsing of the bag.

In testimony whereof, I have signed my name to this specification.

GEORGE W. BANISTER.
